STOCKING MENDING MACHINE

Méropée Sagnier, Paris, France

Application November 28, 1945, Serial No. 631,340
In France May 21, 1943Section 1, Public Law 690, August 8, 1946
Patent expires May 21, 1963

3 Claims. (Cl. 66—1.5)

1

This invention relates to improvements in machines for mending hosiery, e. g. stockings.

Generally, machines of that kind comprise a knitting needle movable within a sleeve to be held with the hand and to which the reciprocatory motion necessary for the mending operation is imparted automatically by a motor or the like through the medium of flexible transmission means whereby the operator is enabled to move the needle along the article to be mended which is stretched on a drum.

According to this invention, the needle-actuating means are housed in a casing; moreover, the drum on which the article is to be stretched for the mending thereof is rigidly connected with said casing and arranged e. g. at the top of the same.

The invention also aims at an improvement whereby the stroke of the needle can be adjusted in a particularly simple and accurate manner.

According to this improvement, the shaft of the prime mover acts upon the flexible connecting means (a Bowden wire, a compressed air connection, etc.,) through the medium of a double eccentric, which makes it possible, by altering the set of the inner eccentric, to modify the actual radius of eccentricity of the outer eccentric (which controls the flexible connection) with respect to the shaft from zero up to a maximum value. This very compact mechanism is contained in the casing, with the exception of a pair of setting knobs.

A stocking mending machine is thus obtained, according to this invention, which is extremely compact, in which the number of parts is reduced to a minimum, which is very reliable in operation and which needs almost no attention.

Further features and peculiarities of this invention will be pointed out in the course of the following description in which reference is had to the appended drawing in which an embodiment of a mending machine according to the invention is shown diagrammatically by way of mere example.

In the drawing:

Figure 1 is an elevational view of the outside of the machine.

Figure 2 is a longitudinal cross sectional view.

Figure 3 is an enlarged horizontal sectional view of the double eccentric mechanism for the actuation of the needle and the adjustment of the stroke thereof.

Figure 4 is a detail view.

Figure 5 and 5a are elevational views of the double-eccentric in either of its end positions.

2

In the example shown the invention is assumed to be applied to a stocking mending machine. It is to be understood however that the same machine, after minor alterations or even as such, can be used for mending any other kind of hosiery.

The machine shown primarily comprises a casing 1 in which the prime mover is arranged, for instance an electric motor 3. Attached to the top of said casing is the drum 2 on which the operator lays and stretches the stocking or like article to be mended.

Through the medium of a reduction gear 4 the motor 3 drives a shaft 5 that carries a driving disc 6 on which the double-eccentric actuating and adjusting mechanism of the flexible transmission means is frictionally fitted.

The said mechanism is shown in enlarged view in Figs. 3 and 4; it is composed primarily of a first eccentric disc 8 rigid with a sleeve 8a rotatably fitted on the jack shaft 5. In turn, said first eccentric disc has rotatably fitted thereon a second eccentric disc 7 which in the example shown has the same radius of eccentricity as disc 8.

The jack shaft 5 and sleeve 8a project through the casing 1 and are borne in a ball bushing 14. The outer end of shaft 5 carries a knob 13 while another knob 12 is carried by the outer end of sleeve 8a.

It will be appreciated that once the shaft 5 is held fast by hand or otherwise by means of knob 13 it is possible, by rotating the eccentric disc 8 by acting upon knob 12, to correspondingly change the actual radius of eccentricity of the second disc 7 with respect to the axis of shaft 5. In the example shown such radius of eccentricity can be varied from a maximum value, corresponding to the position shown in Fig. 5, down to zero, which corresponds to the position illustrated in Fig. 5a.

Surrounding the eccentric disc 7 is an eccentric strap 9 whereby, through the medium of a rod 10, a reciprocatory motion is imparted to the related end of the flexible connecting means (to be described hereinafter) whose amplitude can be adjusted by means of the adjusting mechanism described hereinbefore.

In the operation of the machine, the sleeve 8a is operatively connected with shaft 5 as a result of a stud 23 at one end of a spring arm 22 fast with shaft 5 engaging that hole 24 of a series drilled through knob 12 which corresponds to the desired needle stroke adjustment (Figs. 3 and 4).

As to the outer eccentric disc 7, it partakes of

the same rotational motion through the medium of a crank pin 7a screwed in the side of eccentric disc 7 and variously positioned in a radial slot 6a in disc 6 depending on the relative set of the eccentric discs.

In the example shown in the drawing the flexible connecting means is of the so-called Bowden type, comprising a wire 17 surrounded by a sheath 15. Shown at 16b is the connection between said sheath and the guide sleeve 11 secured to the casing 1, while 16a designates the connection between the sheath and the needle-carrying sleeve 18. Slidably received in said sleeve 18 is a plunger 19 carrying the needle 21 which can be of any suitable type; the related end of wire 17 is fastened directly to said plunger; a tension spring 20 is interposed between the needle-carrying plunger 19 and the bottom of sleeve 18.

The machine thus described operates as follows: After the motor 3 has been started the eccentric strap 9 imparts a reciprocatory motion to the wire 17, whereby a similar motion is imparted to plunger 19 and consequently to needle 21. The operator who holds the sleeve 18 in his hand has then nothing else to do than travelling the needle 21 along the row of loose stitches in the stocking stretched on drum 2; the mending process then takes place automatically.

The stroke of the needle must be adjusted in dependency on the thickness of the article. In this machine such needle stroke adjustment can be carried out most easily and accurately since it is only necessary so to act upon the knob 12 as to bring the spring arm 22 in register with the desired hole in said knob.

As will be clearly understood from the preceding description, the machine according to this invention comprises as few parts as possible and is very reliable in operation. This enables the machine to be operated for a long time with almost no attention. Moreover, an advantage of the same is that the driving mechanism and the stretcher are combined into one single unit.

The embodiment of the flexible connecting means as a Bowden wire has been shown only

by way of example; it is to be understood that any other suitable mechanical, pneumatic or like connecting means can be resorted to.

Besides, it is obvious that this invention has been shown here for explanatory but by no means limitary purposes, and that modifications can be made therein without altering its spirit. For instance, the pair of eccentrics can be substituted by other equivalent members, such as suitable co-operating cams.

What I claim as my invention and desire to secure by Letters Patent is:

1. A machine for mending hosiery articles comprising a casing, a driving mechanism within said casing, a needle-carrying sleeve, a needle assembly slidably received in said sleeve, flexible connecting means between said needle and the driving mechanism and a drum stretcher secured on said casing and serving to support the article to be mended.
2. A machine for mending hosiery articles as claimed in claim 1 wherein the driving mechanism comprises a pair of eccentric discs one of which is loosely mounted on the driving shaft while the other has a pin connection with the same, surrounds the one first mentioned and can be set at various angles with respect to the same for the purpose of altering the stroke of the reciprocatory motion that can be imparted to the needle by the said combination of eccentric discs.
3. A machine for mending hosiery articles as claimed in claim 1 wherein the reciprocation of the mending needle is controlled by a mechanism comprising a driving shaft, an adjusting knob and a crank secured on said shaft, an idle eccentric disc on said shaft, a disc rigid with said eccentric disc and adjacent to said knob, means to couple said disc with said knob in various angular positions, an additional eccentric disc surrounding the first-mentioned eccentric disc and having a pin connection with said crank, a strap surrounding the latter eccentric disc and flexible connecting means between said strap and the needle.
